WELL FLUID CONTROL

Donovan B. Grable, Long Beach, Calif.

Application July 20, 1946, Serial No. 685,236

7 Claims. (Cl. 166—16)

1

This invention has to do generally with the control at the ground surface of fluid contained in oil well pipe strings, during the operation of pulling the pipe string from the well, and also, if the occasion arises, in the course of running a pipe string into the well.

To briefly relate the customary procedure, in pulling pipe from the well, the pipe string is raised successive intervals corresponding to the length of the successive sections or stands making up the string, and the stands are progressively disconnected and stacked to one side in the derrick. Some or all of the sections being disconnected may contain well fluid, e. g. circulating mud, for any of various reasons, including the existence of sufficient well pressure to force the fluid up into the top sections of the pipe string. Accordingly, when the top stand is disconnected, fluid is dumped from the pipe, either openly into the derrick floor and into the cellar below or within one of the kinds of improvised guards that have been used to baffle the fluid against open spraying and otherwise uncontrolled flow.

In running pipe into the well successive stands are added between corresponding lowerings of the pipe string. Under certain circumstances, as when the pipe is being run in against pressure tending to create flow through the string, it may be desirable to maintain the latter closed against fluid escape.

One object of the invention is to provide for the control and removal to a remote location, of well fluid discharging from the stands being disconnected, and in so doing, to obviate the various apparent objections to dumping the fluid openly onto the derrick floor and in the direct working area.

Briefly, this object is accomplished by the provision of a mud receptacle applicable to the pipe string, at any joint, in a manner causing the receptacle to form a substantially fluid-tight closure about the joint sections as they are disconnected. Particularly the invention contemplates the use of a power unit in conjunction with a sectional receptacle whereby the latter may be tightly constricted about the pipe. Fluid line connections with the receptacle permit withdrawal of well fluid to any remote location as well as the introduction of flushing or pressurizing fluid.

A further important object of the invention is the provision of means operable in conjunction with the closure or receptacle, for maintaining the pipe string in closed condition while either

2

adding or disconnecting pipe stands. Specifically the invention contemplates sequentially closing (against well fluid escape) successive pipe stands by plugs to be contained in the receptacle and operable from its exterior to apply the plug to or remove it from the pipe.

As will appear, the invention results in a novel apparatus involving the sequential use of closures or plugs to seal successive pipe stands being run into or removed from the well, and the maintenance through the closure afforded by the mud receptacle, of a continuously effective seal against well fluid escape from the pipe string proper. The particular sequence of operations involved will develop as the description proceeds.

The invention further contemplates an improved apparatus and type of plug for closing the upper end of a pipe stand being removed from the string, as where the plug is inserted into the top of the string before its elevation, and then is removed from the disconnected stand. The type and use of the plug are distinctly characterized by the capacity of the plug, after its effective disconnection from the top of the pipe stand, to be dropped through the pipe for reuse at the derrick floor, thus eliminating the hazards of otherwise handling plugs at an elevated location from which a plug might accidentally be dropped onto workmen at the derrick floor below.

All the above stated objects of the invention, as well as various additional features and the details of certain typical embodiments, will be understood from the following description of the accompanying drawings, illustrative of such embodiments, and in which:

Fig. 1 is a side elevation illustrating one form of mud receptacle embodying the invention;

Fig. 2 is a cross-section on line 2—2 of Fig. 1 showing the receptacle in closed condition;

Fig. 3 is a similar view showing the receptacle in open condition;

Fig. 4 is an enlarged vertical sectional view taken on line 4—4 of Fig. 1;

Fig. 5 is a vertical section taken in the plane at right angles to the view of Fig. 4 as indicated by line 5—5 of Fig. 6;

Fig. 6 is a cross-section on line 6—6 of Fig. 5;

Fig. 7 is a general view showing a suspended pipe stand for attachment to the pipe string below, and illustrative of the operation of a variational form of the invention;

Fig. 8 is a sectional view showing a typical form of plug for use in the variational form appearing in Fig. 9;

Fig. 9 is a vertical sectional view illustrating the use of the mud receptacle in conjunction with a closure for sealing the pipe string;

Fig. 10 is a cross-section on line 10—10 of Fig. 9;

Fig. 11 is a fragmentary enlargement showing the plug control stem seal;

Fig. 12 is a view generally similar to Fig. 9 illustrating a further variational form of the invention;

Fig. 13 is a cross-sectional view showing the plug used in the apparatus of Fig. 12; and

Fig. 14 is a fragmentary enlargement showing the sealed connection between the plug stem and the control tube.

Referring first to Fig. 1, the mud receptacle assembly includes a tubular body, generally indicated at 10 adapted to be applied about the well pipe string 11 at the conventionally illustrated coupling or joint 12, in a manner preventing any substantial leakage of well fluid from the pipe string with the joint in open or uncoupled condition. The receptacle body 10 comprises a pair of sections 13 and 14 having a hinge connection at 151 permitting the sections to be applied to the pipe in the open condition of Fig. 3, and constricted about the pipe to the closed position of Fig. 6.

While the body 10 may be made of any suitable material, typically the sections 13 and 14 may be formed of rubber within the top and bottom ends of which may be embedded the semi-circular metallic re-enforcing channel bars 15 and 16 interconnected by the longitudinal re-enforcing rods 17 and members 18 and 19 extending longitudinally of the sections adjacent their interengageable edges, as shown in Fig. 6. Any suitable additional re-enforcement may be used to serve the purpose of force transmission to the sections at the hinge 151. As illustrative, the sections 13 and 14 are shown to contain, respectively above and below the longitudinal center of the receptacle, semi-circular re-enforcements consisting of plates 20 and 21 having interconnections 22 and attached at their edges to members 18 and 19. Plates 20 in turn are attached to the hinge sections 23. The successive hinge sections 24 and 25 are attached respectively to the re-enforcement in the sections 13 and 14, and a pin 26 is inserted through the series of hinge sections. Thus as previously indicated, the body sections 13 and 14 are capable of swinging about the hinge pin 26 between the positions of Figs. 2 and 3.

Swinging of the body sections 13 and 14 about the hinge pin is effected by a piston and cylinder assembly generally indicated at 27, and comprising a cylinder 28 mounted to the hinge pin by a pair of members 29 and 30 attached to the cylinder by screws 31, the upper member 29 having a handle 32 to facilitate bodily manipulation of the apparatus. Cylinder 28 contains a piston 33, the rod 34 of which has a pivotal connection at 341 with links 35 pivotally connected at 351 with a pair of plate lugs 36 attached respectively to the re-enforcing members 20 of the respective body sections. As will be apparent, reciprocation of the piston 33 in opposite directions, expands and constricts the body sections between the positions of Figs. 2 and 3. Pressure fluid is delivered to and discharged from the cylinder 28 through suitable connections such as the high pressure and exhaust lines 37 and 38.

With the body 10 constricted about the pipe 11, provision is made for maintaining a fluid pres-

sure responsive seal between the pipe and the end portions of the body. Such seal may be effected by forming the rubber body material with internal annular lips 40 which become tightly pressed by the internal body pressure against the pipe to maintain a seal preventing at least any considerable leakage of fluid from the body along the pipe. The top portion of the body has connections through check valves 41 and 42 with water and air hoses 43 and 44, and at its lower end the body connects at 45 with a discharge hose 46 through which fluids may be discharged from the body to any location remote therefrom.

In considering the operation of the described assembly, assume that the mud receptacle is to be used during pulling of the pipe string from the well, to conduct mud or circulating fluid from successive pipe stands being disconnected, to a mud basin or other location away from the pipe and derrick floor. Suspended on a line 47 attached to the hinge pin 26, the receptacle assembly is swung against the pipe and piston 33 actuated to close the body section about the pipe, see Fig. 6, with the joint 12 contained in the body. The upper pipe stand 11a then is rotated to disconnect it from the pipe string below. Upon breaking of the joint 12, the mud column in the pipe stand 11a discharges into the body 10 and is conducted away through the hose 46. Thereafter the interior of the body may be flushed clear of residual mud by the discharge of either or both of water or air from lines 43 and 44 through the body. The latter then is opened to release the stand 11a for removal to one side in the derrick, following which the pipe string is raised a successive stand length and the described operation repeated.

Figs. 7 through 14 illustrate variational embodiments of the invention capable of use as mud receptacles generally in accordance with the described procedure, but having the additional capacity for use in conjunction with closures applied to the pipe string to maintain the latter sealed against well fluid discharge as the pipe string length is varied at the ground surface, either by the addition or disconnection of pipe stands. Referring to Fig. 7, the usual procedure in pulling the pipe string from the well is to engage the top stand 11a with an elevator 59 and to raise the string until the stand 11b below can be engaged and the well string supported by slips 51 in the rotary table 52. After rotation to disconnect the joint 12, the stand 11a is stacked to one side and the elevator lowered to engage and withdraw the stand 11b below. In running pipe into the well, the stand 11a to be connected to the string supported by the table slips 51, is lowered and rotated to make up the joint 12, and the entire string is raised to permit release of the slips and then lowered to engage the top stand with the slips for connection of a successive stand.

Referring now to Figs. 9 and 10, the mud receptacle 53 comprises a body made in sections 54 and 55, for example of internally re-enforced rubber in the manner of the previously described receptacle 10, as will be understood without necessity for illustration of the particularities of the re-enforcement. As before, sections 54 and 55 are interconnected by hinge 56 and actuated to swing apart and together about the hinge by way of the piston rod 57 and its pivoted link connections 58 with members 59 connected respectively to the body sections. The valved water and air lines 60 and 61 connected through the check

valves 62 with the upper interior of the body, and the valved discharge line 63 leads from the bottom of the body. Where the receptacle 53 is to be used merely for confining fluid discharge from the upper stand 11a upon breaking the joint, so that the fluid may be conducted away through line 63, the operation of the assembly will correspond to the previous description of Figs. 1 to 6.

The receptacles shown in Figs. 9 and 12 however are constructed to serve the further purpose of containers for closures to be applied to the pipe string for sealing off fluid discharge from the well, as and in the manner now to be described. Referring to Fig. 9, the body section 55 is shaped to provide a cavity 64 offset with relation to the pipe string and closed at its outside by a self-sealing door 65 hinged to the body at 66 and releasably held closed by a suitable latch 67 operated by the handle 68. Cavity 64 contains a plug, generally indicated at 69, suspended on rod 70 extending through a universal sealed joint 71 in the body. As illustrated in Fig. 11, the joint 71 may comprise a ball member 72 through which rod 70 extends within the packing rings 73, the ball being confined against spherical seats 74 and 75 on the body and retaining nut 76. Packing ring 77 prevents fluid leakage about the ball. In the broad aspects of the invention, the plug 69 may be of any suitable type capable of insertion within the lower stand 11b to maintain the well string closed against fluid escape until the stand is disconnected according to the later described procedure. Preferably, I use a type of plug which is self-sealing upon insertion into the pipe, and which later may be released, upon elevation of the stand, so that the plug may be dropped through the stand to the derrick floor for reuse.

Referring to Fig. 8, the plug 69 comprises a tubular body 78 containing a bore 79 and at its lower end a counterbore 80 containing a check valve 81 normally seated against shoulder 82 by coil spring 83 retained by the apertured plug 84. The valve 81 is carried on the lower end of rod 85 centered within the bore by lugs 86 and having on its upper end a spherical knob 87 engaged by spring fingers 88 on the control stem 70. The body 78 is movable vertically relative to sleeve 89 having an upwardly tapered wedge surface 90 engaged by slips 91 so that upon upward relative movement of the wedge sleeve, the slips are thrust outwardly to grip the pipe. Below sleeve 89 the body carries an annular packing sleeve 92 expandable by upward relative movement of the tapered body surface 93 to expand the sleeve into fluid-tight engagement within the pipe. Above the slips, the reduced diameter portion 78a of the body carries a sleeve 94 retained by ring 95 and supporting an expandable rubber capsule 96 to which air is supplied through stem 97 containing the usual type of tire valve 98.

In considering the operation of the assembly, assume the receptacle 53 to be placed about the pipe string at the joint before it is disconnected, with the body sections 54 and 55 tightly pressed together to close against fluid leakage. Assuming also the upper stand 11a to be closed at its top by a plug 69, the joint is then disconnected and its sections separated as in the condition shown in Fig. 9. Rod 70 now may be manipulated from the outside of the receptacle to lower the plug 69 into the upper end of the pipe stand 11b, as within the coupling 100 so that the slips 91 are engageable with the coupling bore 101 and the packing ring 92 is thrust down into the pipe proper. Before insertion of the plug in the re-

ceptacle, the capsule 96 will have been inflated with air introduced through the stem 97 and the capsule thus expanded so that when lowered into the pipe stand, as illustrated by the dotted line position of the parts, the expanded condition of the capsule will retain the plug in proper seating position. Where pressure equalization is necessary to facilitate insertion in seating of the plug, fluid may be introduced through lines 60 or 61 (valve 102 in the discharge line being closed) to develop whatever pressure desired in the receptacle.

The plug 69 is self-engaging and sealing under the influence of fluid pressure in the well pipe string, by reason of the tendency of the pressure acting against the body 78 to expand the packing sleeve 92 and cause radial expansion of the slips 91 in response to upward relative movement of the wedge sleeve 89. Upon insertion of the plug, rod 70 may be detached from the stem 85 by pulling spring fingers 88 from the knob 87. Valve 102 then may be opened to discharge fluid draining into the receptacle from stand 11a. If desired, the operator up in the derrick may depress stem 85 in the plug contained in the top stand 11a, to open the valve 81 and admit sufficient air to assure complete dumping of fluid from the stand. After flushing out the receptacle, the latter may be opened and removed from the pipe, to permit the disconnected stand to be placed to one side. The plug 69 in the top of the stand is retrieved for reuse by release by the derrick operator of air from the capsule 96 through the valve 98, whereupon in its deflated condition, the capsule will permit the plug to drop down through the pipe stand onto the derrick floor. Any tendency for the packing sleeve 92 or slips 91 to adhere within the pipe, may be relieved by striking or otherwise depressing rod 85 to move the body 78 down from expanding relation to the packer and slips. Fig. 7 illustrates the condition of the pipe string after removal of the mud receptacle, the lower section 11b being closed by plug 69a, and the upper end of stand 11a being closed by plug 69b before the latter is released to be dropped through the stand. Thereafter the elevator 58 is applied to the stand 11b, the string raised, and the described procedure repeated.

Figs. 12 to 14 illustrate a type of plug useable for maintaining the pipe string closed while adding pipe stands to the string in the course of its being run into the well. This same type of plug and control may, however, also be used in the general manner of the previously described plug, for maintaining the pipe string closed while it is being pulled from the well. Here the plug 105, see Fig. 13, comprises a body 106 carrying an inflatable rubber capsule 107 to which fluid is introduced through a tubular stem 108 by way of passages 140 and 141. Stem 108 may carry a suitable valve or cock 109 for opening or closing air communication through the stem, and preferably sufficiently small in size as to pass with the plug down through the pipe when the plug is released as will later appear. Stem 108 above the valve has a flexible sealed connection 110 with a tubular rod 111 extending through joint 112 (corresponding to the previously described joint 71) and connecting with an air hose 113 through a T-fitting 114 which includes the air supply control valve 115 and the release valve 116. The flexible joint at 110 comprises a spherical head 117 on the stem 108, seating against spherical surfaces 118 and 119 on the nut and

body sections 120 and 121 of the coupling, fluid leakage about the knob being prevented by seal ring 122.

Assume that it is desired to seal the well pipe string against fluid escape while running pipe into the hole, and that the top of the string to which the stand 11a is to be attached, is closed by the plug 105. As illustrated in Fig. 12, the plug may be seated within the typical form of tool joint illustrated, by inserting the capsule 107 opposite the annular space 124 directly beyond the end of the pipe and expanded by introduction of air through stem 108 (followed by closing of the valve 109) to tightly expand the plug in position. Stand 11a then is lowered to the position of Fig. 12 and the mud receptacle 125 closed about the pipe sections. Previously or thereafter, the upper end of stand 11a is closed by a plug 105 by inflation of its capsule by the operator up in the derrick. Door 126 then may be opened to permit connection of the joint 110. Valves 115 and 116 being closed, valve 109 may be opened to place the plug stem and tube 111 in communication. The door then is closed and following any required pressure equalization through introduction of fluid to the receptacle, the release valve 116 is opened to cause deflation of the capsule and permit removal of the plug into the offset cavity 127. The pipe joint may then be completed and the receptacle 125 removed.

Assume the top stand in the pipe string to be closed at its upper end by plug 105, and the string to be raised for disconnection of the plug-contained stand with the pipe stand next below. The receptacle 125 is closed about the joint to be disconnected, and the upper stand rotated to break the joint and permit the joint sections to assume spaced relations in Fig. 12. A deflated plug 105 previously suspended in cavity 127 on the tube 111, is then lowered by manipulation of the rod into seating position within the stand 11b. During that time, valves 115 and 116 will remain closed. With the plug inserted in the pipe, valve 115 then is opened to admit air to the plug and expanded into sealing relation with the pipe. Valve 102 then may be opened to drain all fluids from the receptacle. By then opening door 126 access may be had to the parts in order that valve 109 may be closed to retain the plug in inflated condition, and the joint at 110 disconnected to free the tube 111. The receptacle then is removed, following which the plug in the upper end of stand 11a may be deflated by opening its air valve, and the plug dropped through the pipe. The pipe string then is raised to expose a successive joint for disconnection, and the above described procedure repeated.

If for any reason the receptacles 125 or 53 may be applied to a lower stand 11b without an upper stand 11a being received within the receptacle, and suddenly developed well pressure tends under any circumstance to discharge fluid from the string, the receptacle may be provided with a blow-out preventer operable to close off the escape of well fluid. Such blow-out preventer may consist of a plug 128 hinged to the body at 129 in a position such that the plug may swing upwardly into and close the opening 130. Such movement of the plug may be caused by a spring 131 supported about pin 132 and bearing against the plug, as illustrated. Normally the plug will be held in open position by a screw retainer 133 which may be rotated to release the plug for closure under the influence of the spring.

when the occasion arises for suddenly closing the opening 130.

I claim:

1. An oil well mud receptacle comprising a tubular body including a pair of sections adapted to be placed about a well pipe joint, a hinge interconnecting said sections, a cylinder connected to said body, and a piston in said cylinder and connected to said sections for tightly constricting them about the pipe.
2. An oil well mud receptacle comprising a tubular body including a pair of sections adapted to be placed about a well pipe joint, a hinge interconnecting said sections, a cylinder connected to said body at the hinge, a piston in said cylinder and connected to said sections for tightly constricting them about the pipe, and means for suspending the body and cylinder assembly.
3. An oil well mud receptacle comprising a tubular body including a pair of sections adapted to be placed about a well pipe joint, a hinge including a vertically extending pin interconnecting said sections, means for attaching said pin to a suspension line, a cylinder attached to said pin, and a piston in said cylinder and connected to said sections for tightly constricting them about the pipe.
4. A tubular mud receptacle body comprising relatively movable longitudinal sections adapted to be opened and closed about a well pipe joint connecting upper and lower pipe sections, said body containing a laterally offset chamber, a plug contained in said body initially within said offset chamber for closing application to the upper end of said lower section when the joint is broken and said lower section remains in the body, and control mechanism mounted on the exterior of said body and including means extending into the interior of the body and releasably attachable to the plug, said mechanism being operable from the outside of the body to move the plug into closing engagement with the end of the lower pipe section within the body when the pipe joint is broken.
5. The combination comprising a tubular mud receptacle body including relatively movable sections adapted to be opened and closed about a well pipe joint connecting upper and lower pipe sections, a pipe closing plug carried by and inside said body and in offset relation to the pipe, and control mechanism mounted on the exterior of said body and including means extending into the interior of the body and releasably attachable to the plug, said mechanism being operable from the outside of the body to move the plug into closing engagement with the end of the lower pipe section within the body when the pipe joint is broken.
6. A tubular mud receptacle body comprising relatively movable longitudinal sections adapted to be opened and closed about a well pipe joint connecting upper and lower pipe sections, a plug contained in said body for closing application to the upper end of said lower section when the joint is broken and said lower section remains in the body, a mechanism carried by said body on and operable from the exterior thereof extending into the interior of the body and detachably engaged with said plug to manipulate and apply the plug inside the body to said lower pipe section when the body is closed about the pipe, and means connected to said body for communicating pressure fluid to the inside of the closed body.
7. A tubular mud receptacle body comprising

relatively movable longitudinal sections adapted to be opened and closed about a well pipe joint connecting upper and lower pipe sections, a plug contained in said body for closing application to the upper end of said lower section when the joint is broken and said lower section remains in the body, a mechanism carried by said body on and operable from the exterior thereof extending into the interior of said body detachably engaged with said plug to manipulate the plug inside the body to said lower pipe section when the body is closed about the pipe, and a blow out preventer on said body for closing the opening in the body through which said upper section extends.
